UNITED STATES PATENT OFFICE

2,618,274

SCALP PROTECTOR

Edith L. Nell, Bridgeport, Ill.

Application October 28, 1949, Serial No. 124,080

2 Claims. (Cl. 132—9)

1

This invention relates to a scalp and hair protector primarily adapted to be worn during application of a cold wave solution and adapted also to be worn during a hot wave application, the primary object of the invention being to provide an efficient and practical device of this kind which prevents the waving solution and the rinsing and setting solutions from reaching and wetting the scalp and portions of the hair other than those to which the solution or solutions are designedly applied, thereby preventing damage or other undesired effects upon the hair and scalp.

Other important objects and advantageous features of my invention will be apparent from the following description and the accompanying drawings, wherein, merely for purposes of illustration herein, a specific embodiment of the invention is set forth in detail.

In the drawings:

Figure 1 is a plan view of the device with hair-lock clamps and clips removed;

Figure 2 is a perspective view showing the device in use and partly broken away to show underlying structure;

Figure 3 is a top plan view of one of the clips;

Figure 4 is a fragmentary vertical longitudinal section taken on the line 4—4 of Figure 1;

Figure 5 is an enlarged fragmentary vertical longitudinal section taken on the line 5—5 of Figure 1;

Figure 6 is an enlarged fragmentary bottom plan view taken along the line 6—6 of Figure 5;

Figure 7 is a transverse vertical section taken on the line 7—7 of Figure 3;

Figure 8 is an enlarged fragmentary transverse vertical section taken on the line 8—8 of Figure 2, showing the arrangement of one of the clamps.

Referring in detail to the drawings, wherein like numerals designate like parts throughout the several views, the illustrated device comprises a generally-rectangular sheet 10 of suitable plastic or other solution-resistant material forming a covering for a head 11 to enclose the hair thereof except for selected locks or tresses 12 to which the waving and setting solutions are to be selectively applied.

The head covering 10 has a tubular edging 13 formed by turning under and sewing or otherwise securing the same, as indicated at 14. Near the rearward end the covering 10 has secured to the under side thereof, as by two lines 15, 15 of sewing, and extending across the covering parallel to its rearward end, a tube 16 formed of

suitable flexible material with its edges turned in and anchored by the sewing lines 15. The ends of the tube 16 communicate with the tubular edging 13 extending forwardly from the tube, and a drawstring 17 is disposed in the tube 16 and the forward portions of the edging 13, including that portion along the forward edge of the covering. The terminals 18 of the drawstring 17 are lead through an opening in the tube 16 for tying after the covering has been constricted on a head 11 in a well-known manner, to cause the covering 10 to conform closely to the head 11.

The covering is formed with transverse rows of transversely-elongated slots 19 having edges 20 turned under and sewed or otherwise suitably secured, as indicated at 21 and 21' in Figure 5. The rows may be of varying length, as shown in Figure 1, and the slots 19 are spaced at intervals corresponding with the usual or desired spacing 20 on the head 11 of the locks or tresses 12 to be waved.

The slots 19 not in use are closed by closure sheets 22 secured in suitable manner, as indicated in Figure 6, to the under side of the covering 10 around the edges of the slots and are adapted to be easily removed to expose the desired slots 19.

The tresses 12 to which waving or other treating solution is to be applied, having been selected, are inserted in the slits 24 formed intermediate the side edges of suitable, resilient, compressible-material clamps 25 of rectangular shape, as indicated in Figure 8 and in Figure 2, and the portions of the tresses projecting upwardly from the clamps 25 are then passed upwardly through the proper slots 19 in the covering with the clamps positioned against the under side of the covering 10. The clamps 25 extend on all sides of the slots 19 and when in place act as dams to prevent solution applied at the top of the covering 10 and reaching the slots 19 from passing through these slots and wetting the hair and scalp beneath the covering 10.

The tresses 12 rising through the slots 19, which are the tresses to which the cold-waving and other solutions are to be applied, are wedged in the diametrical slits 26 of resilient, non-metallic-disc clips 27, whereby the resilient clamps 25 are drawn up tight against the under side of the covering to effectively dam the slots 19.

The clips 27 have the edges of their slits 26 turned up to provide parallel flanges 26', as indicated in Figure 7, to provide adequate spacing of these flanges for reception of a tress 12 and to provide adequate frictional grip of these flanges

on the tress. The end of the slit 26 opening through the edge of the disc has edge portions 28 which are downturned along each other with one edge portion provided with an extension 29 which is bent upwardly around the other edge portion 28 to close and prevent spreading of the slit 26. As shown in Figure 7, the clip 27 is upwardly dished so as to exert tension on the top of the covering 10 in opposition to the engagement of a clamp 25 with the under side of the covering when a tress is pulled frictionally through the clip slot 26 and the clip is compressed downwardly to produce the tension between the clamp 25 and the clip 27. The flanges 26' provide mounting means for suitable tress-winding elements 30.

What is claimed is:

1. A covering for use in hair waving comprising a rectangular shaped sheet fabricated of solution resistant material and having a tubular edging extending therearound, a tube extending transversely of said sheet inwardly of and spaced from the rearward end of said sheet and having each of its ends in communication with the adjacent portion of said tubular edging, there being an opening in said tube intermediate its ends thereof, and a drawstring extending through and about the portion of the tubular edging forwardly of said tube and through said tube and having its ends projecting out of the tube opening and terminating at a point spaced from said tube, the portion of said sheet intermediate the forward end thereof and said tube being provided with a plurality of rows of slots arranged in transverse spaced parallel relation, the slots of each row extending transversely of said sheet and each adapted for extension of a tress of hair therethrough.

2. A covering for use in hair waving comprising a rectangular shaped sheet fabricated of solution

resistant material and having a tubular edging extending therearound, a tube extending transversely of said sheet inwardly of and spaced from the rearward end of said sheet and having each of its ends in communication with the adjacent portion of said tubular edging, there being an opening in said tube intermediate its ends thereof, a drawstring extending through and about the portion of the tubular edging forwardly of said tube and through said tube and having its ends projecting out of the tube opening and terminating at a point spaced from said tube, the portion of said sheet intermediate the forward end thereof and said tube being provided with a plurality of rows of slots arranged in transverse spaced parallel relation, the slots of each row extending transversely of said sheet and each adapted for extension of a tress of hair therethrough, and a detachable closure sheet covering each of said slots.
